UNITED STATES PATENT OFFICE.

EUGENE W. CARUTHERS, OF SECANE, PENNSYLVANIA.

RAIL JOINT.

Application filed July 26, 1928. Serial No. 295,401.

My invention relates to a splice joint for the rails of railroad tracks with particular reference to a method for avoiding stresses at the ends of the rails, stresses that have 5 hitherto been a frequent cause of ultimate rail failure.

A purpose of my invention is to avoid stresses in the webs of rails at the ends of the rails incident to rail creeping or rail deflection under rolling trains, either or both, by 10 avoiding any engagement between the rail web and a track bolt close to the rail end.

A further purpose is to provide the splice bar track bolt at a rail end with a larger 15 range of clearance from the rail web than the clearance range for the track bolt or bolts less near the rail end so that stresses incident to rail creeping or rail deflection under traveling trains will be supported at the track 20 bolts further away from the rail end, thus avoiding the repeated application of these heavy stresses in a portion of the rail web that is very close to the rail end. I carry the load incident to rail creeping and rail deflections 25 upon a portion of the rail web that is somewhat removed from the rail end and upon the flanges of the splice bars.

A further purpose is to give such clearance 30 at the bolt holes nearest the rail ends that splice bar displacements from any cause whatever will not cause engagement between the bolts and the walls of these bolt holes.

Further purposes will appear in the specification and in the claims.

I have elected to show one form only of my 35 invention with a few minor modifications, selecting a form that is practical and efficient in operation and which well illustrates the principles involved.

Figure 1 is a side elevation intended for a 40 conventional illustration of any splice bar rail joint of the prior art, one of the splice bars being broken away to show the track bolts and perforations through the rail webs.

Figure 2 is a section of Figure 1 taken upon 45 the line 2-2 thereof.

Figures 3 to 6 are side elevations illustrating slightly different forms of my invention.

Like numerals refer to like parts in all figures.

Describing in illustration and not in limitation and referring to the drawings:—

In the conventional illustration the abut-

ting ends of rails 10 and 11 are joined by means of splice bars 12 and 13 and bolts 14, 55 15, 16 and 17 through perforations 18, 19, 20 and 21 in the rail webs.

Obviously the location of the ties or supporting structure is immaterial to the application of my invention.

The rail ends are seated on suitable tie plates 22 and are spiked down to the ties 23 through the tie plates by spikes 24.

All of this structure is intended for a mere conventional illustration for any suitable 65 splice bar rail joint of the prior art, and the splice bars may or may not be anchored at the rail joint to the ties.

In the past the need for a rail replacement 70 on a railroad has been frequently determined by the presence of one or more cracks or ruptures 25 radiating at a rail end from a perforation 19 or 20 (Figure 1), that is near the rail end.

These cracks, or ruptures, have been incident 75 to service and appear to have been due to temperature changes and to relative displacement of the party at this joint. It is accentuated by repeated sudden depressions of the rail ends as trains roll over the joint, with the 80 joint already under heavy tension stresses incident to rail creeping.

The conventional joint of Figure 1 is indicated as in this condition of tension, the 85 rails 10 and 11 being shown as tending to pull apart away from the joint, so that the bolts 14 and 15 of the rail 10 engage the edges of the perforations 18 and 19 that are nearest to the end of rail 10 and the bolts 16 and 17 of rail 11 engage the rail web at the end side of 90 their perforations 20 and 21.

This condition of tension at a rail joint has been a frequent one after the rails have seen considerable service even during the periods 95 when the joint is not supporting a train, and has usually been incident to rail creeping. The strains and stresses are greatly increased at such a joint during the time that trains are rolling over the joint and by temperature changes.

The heaviest strains during the passage of 100 trains take place at the rail ends and for this reason the bolts 15 and 16 immediately adjacent the rail ends are subjected to the heaviest strains and stresses.

Each passage of a train over the rail 10 re-

sults in heavy stresses in the rail web by reason of the straining engagement between the track bolt 15 and the edge, usually the forward edge of the perforation 19, and these 5 heavy stresses many times repeated cause cracks or failures, as along the lines 25.

The corresponding strains at one or more track bolts 14 further away from the rail end appear not to have resulted in sufficient damage to the rail to be a material factor in 10 determining when a rail needs replacement.

However the cracks and ruptures from the forward side of the hole 19, incident to the heavy and many times repeated strains upon 15 the bolt 15, have frequently been the ultimate determining factor for the rail renewal.

The causes for rail creeping are irrelevant to the present invention which is directed at avoiding the heavy and many times repeated 20 stresses in the rail web at a point so close to the rail end as to become an ultimate determining factor for the rail renewal.

In accord with my invention I avoid the rail web stresses at the holes 19 and 20 by 25 avoiding contacts between the respective rail webs and the bolts 15 and 16 and do this by increasing the clearance ranges of the bolts 15 and 16, (Figure 3), from the sides of the perforations 19 and 20 as compared to the 30 clearance ranges of the bolts 14 and 17 from the sides of the perforations 18 and 21 respectively, or by slightly different centering of the bolts in the rails, the bolts 14 and 17 being those more distant from the respective 35 rail ends.

Though bolts 15 and 16 do not themselves engage the rail webs they are effective to support the rails against pressure and impact due to the passage of trains since they hold 40 the splice bars tightly against the rails and, in particular against the under sides of the rail heads.

I may secure this greater clearance in any 45 suitable way, as by making the perforations 19 and 20 larger than perforations 18 and 21, or by making the bolts 15 and 16 of suitably smaller diameter and of correspondingly better material than that of the bolts 14 and 17, as for example using smaller bolts of alloy 50 steel adjacent the rail ends and bolts of normal size of carbon steel further away from the rail ends, or may give the bolts a spacing such that the rearward bolts engage their hole edges toward the rail ends before 55 such engagement by the bolts 15 and 16 at the rail ends.

In the form of Figure 4 I place a bolt 27 at the middle of the splice bars and between the abutting rail ends which are suitably recessed at 28 and 29 so as to pass the bolt.

In Figures 3 and 4 I show splice bars that have respectively four and three bolts. Obviously the number of bolts may be increased to any desired number and in Figures 5 and 6 I show joints respectively like those of

Figures 3 and 4 except that the splice bars have been provided respectively with six and five bolts instead of the four and three bolts in the joints of Figures 2 and 3.

The forms shown in Figures 5 and 6 are 70 preferable when the creeping forces are very heavy, as the relief of strains upon the bolt or bolts nearest the rail ends throws additional strains upon the bolt or bolts further away from the rail ends.

In operation the tension forces upon the rails are supported by the bolts less near the rail ends and the resultant stresses in the rail webs are sufficiently removed from the rail ends to be no longer a cause for rail failures at the bolt holes that are closely adjacent the rail ends. The result is a materially increased life for the rails.

In view of my invention and disclosure variations and modifications to meet individual whim or particular need will doubtless become evident to others skilled in the art, to obtain all or part of the benefits of my invention without copying the structure shown, and I, therefore, claim all such in so far as 90 they fall within the reasonable spirit and scope of my invention.

Having thus described my invention what I claim as new and desire to secure by Letters Patent is:—

1. The method of reducing breakage of rails at rail joints using splice bars due to stresses incident to engagement of the bolt hole walls in the rail ends against the bolts which consists in relieving the bolt or bolts 100 supporting the splice bars against the rails close to the rail ends from rail tension engagement and taking this rail tension engagement at points farther from the rail ends.

2. The method of avoiding a rail strain or breakage at an extreme rail end and at a splice bar joint having splice bars and having bolts at different distances from the rail end, which consists in avoiding engagement 110 between the rail web and the bolt that is nearest the rail end by supporting the tension forces upon the rail upon the bolt or bolts further away from the rail end.

3. In a railroad, a splice bar joint between 115 adjoining rails and comprising splice bars bolted together upon opposite sides of the rails across the rail ends in which the bolts pass through the rail webs and the bolt of each rail that is closely adjacent to the rail 120 end is provided with sufficient clearance from the rail web to avoid stress engagement of the web with the bolt when the rail joint is under stress.

4. A pair of rails each having a plurality 125 of bolt openings and abutting for a joint, a pair of splice bars on opposite sides of the rail ends having corresponding bolt holes and bolts passing through the apertures, the bolts further from the rail ends receiving trans- 130

verse stress first from the rails before the bolts nearer to the rail ends in order to locate longitudinal tension upon the rail webs primarily further from each rail end than the 5 first bolt hole.

5. In a rail joint, a pair of rail ends, splice bars on opposite sides of these ends, a bolt supporting the splice bars laterally against

the rail ends at the ends of the rails and free from transverse engagement by the rails and 10 other bolts supporting the splice bars laterally against the rails at a distance from the rail ends and with which the rails tensionally engage.

EUGENE W. CARUTHERS.
